(57) **CLAIM**

The ornamental design for a tire tread, as shown and described.

DESCRIPTION

FIG. 1 is a perspective view of a tire tread showing our new design taken from a first side thereof, it being understood that the pattern repeats uniformly throughout the radial circumference of the tread;

FIG. 2 is a detailed sectioned view of the perspective view of FIG. 1;

FIG. 3 is a perspective view of a tire tread showing our new design taken from a first side thereof, it being understood that the pattern repeats uniformly throughout the radial circumference of the tread;

FIG. 4 is a detailed sectioned view of the perspective view of FIG. 3;

FIG. 5 is a first side elevational view thereof;

FIG. 6 is a detailed sectioned view of the first side elevational view of FIG. 5.

FIG. 7 is a second side elevational view thereof;

FIG. 8 is a detailed sectioned view of the second side elevational view of FIG. 7.

FIG. 9 is a top plan view thereof, it being understood that the pattern repeats uniformly throughout the radial circumference of the tread;

FIG. 10 is a detailed sectioned view of the first side of the top plan view of FIG. 9.

FIG. 11 is a detailed sectioned view of the first side of the top plan view of FIG. 9; and,

FIG. 12 is a detailed sectioned view of the second side of the top plan view of FIG. 9.

In the Figures, the evenly spaced broken lines represent unclaimed subject matter, while the dash-dot-dot-dash style broken lines represent boundaries of the claim.
